UNITED STATES PATENT OFFICE.

HENRIETTA PYLES, OF MYRTLE, MISSOURI.

PACKING VESSEL.

SPECIFICATION forming part of Letters Patent No. 627,142, dated June 20, 1899.

Application filed August 2, 1898. Serial No. 687,527. (No model.)

To all whom it may concern:

Be it known that I, HENRIETTA PYLES, a citizen of the United States, residing at Myrtle, in the county of Oregon and State of Missouri, have invented a new and useful Packing Vessel, of which the following is a specification.

This invention relates to improvements in packing vessels; and the object thereof is to provide a simple, cheap, and convenient construction in which articles, such as butter, may be packed and preserved during shipment and storage or while being sold in small quantities by retail merchants.

With the above object in view the invention consists of a wire frame adapted to be removably positioned in the tub, having a central ice-chamber and a plurality of removable shelves.

The invention consists in the novel details of construction hereinafter described in the specification, particularly pointed out in the claim, and illustrated in the accompanying drawings, in which—

Figure 1 is a perspective view of my invention removed from the tub. Fig. 2 is a vertical sectional view of the same in position in the tub. Fig. 3 is a transverse section on the line 3 3 of Fig. 2 with the shelves removed.

Referring now more particularly to the accompanying drawings, A designates a plurality of wire rods bent at their lower ends to form the bottom bars B of the frame, which are crossed and held in position by a wire ring C, secured at the bottom of the frame by bending the rods, as at D, to receive the same, and at their upper ends by a similar ring E, passed through loops or eyes F, formed at the upper ends of said rods. Removably positioned in this frame, at the center thereof, is a cylindrical casing or ice-receptacle G, provided at its upper end with a cap H, held thereon by a swinging bail I, which also serves as a handle for said ice-receptacle. Brackets J are secured about the exterior of said cylinder at different points throughout the length thereof, and the wire rods A are formed with inwardly-extending bends K in line with said brackets, which constitute shoulders or

brackets to receive the removable shelves L, which rest thereon and on the brackets J, 50 said shelves being formed in section and having a central opening to receive the ice-chamber. The wire rods constituting the frame are held in proper position intermediate their ends by the band M.

The frame is placed in the tub N or other similar receptacle, the ice-receptacle positioned therein, and the lower shelf placed upon the supporting-brackets therefor. Butter may then be placed upon said shelf and 60 the next shelf properly positioned, and so on until the vessel has been filled. The ice may then be placed in the ice-chamber and the tub of butter shipped, the same being preserved during shipment. By having the different 65 shelves for the butter, print-butter may be shipped without destroying the design printed thereon.

A packing-ring O is provided for the cap H, so that the water formed by the melted ice 70 will not escape from the ice-chamber and reach the butter.

The packing vessel above described might be used in the store and the butter preserved while sold in small quantities without the use 75 of an ice-chest, as the ice might be renewed from day to day in the ice-chamber, a suitable outlet or drain tube being provided for the latter.

Having thus fully described my invention, 80 what I claim as new, and desire to secure by Letters Patent of the United States, is—

In a packing vessel, the combination with a casing, of a wire frame adapted to be positioned therein and formed with a plurality of 85 inwardly-extending bends, an ice-chamber positioned centrally in said frame and having a plurality of brackets secured to the exterior thereof, and a shelf positioned in said frame and supported by said inwardly-extending 90 bends and brackets, substantially as set forth.

HENRIETTA PYLES.
